UNITED STATES PATENT OFFICE.

WILLIAM F. SCHWEIGER, OF ROCHESTER, NEW YORK, ASSIGNOR TO MULTIPOSTER COMPANY, INCORPORATED, OF ROCHESTER, NEW YORK, A CORPORATION OF NEW YORK.

STAMP-DISPENSING MACHINE.

Application filed November 19, 1924. Serial No. 750,952.

This invention relates to a stamp dispensing machine, of the general type illustrated in Patent No. 1,312,669, August 12, 1919, for holding and dispensing stamps of different denominations.

The principal object of the invention is to afford a structure of few parts and simple in operation, by which any desired number of stamps can be ejected from a container and severed as a unit from the main body or strip of stamps.

More particularly the invention has for a purpose to provide a combined ejecting and severing means for the stamps, together with an actuating device that is operable a given distance to eject a stamp, and which when moved beyond such predetermined distance operates to sever a stamp or series of stamps from the strip.

Another object of the improvement is to afford mechanism that permits a ready and efficient moistening of each stamp as it is ejected, and a common liquid supply for the moistening means of a series of independent stamp housings containing stamps of different denominations.

With these ends in view, the invention includes the structure that will appear clearly from the following description when read in conjunction with the accompanying drawings, the novel features being pointed out in the claims following the description.

In the drawings:

Figure 1 is a front elevation of a machine embodying the features of the invention in a preferred arrangement, and illustrating three stamp containing and dispensing units with the respective actuating devices in three possible positions;

Figure 2 is a plan view of the same; Figure 3 is an end elevation;

Figure 4 is a vertical sectional view taken centrally of one of the stamp containing units or housings, and showing the actuating device in uppermost position;

Figure 5 is a similar view enlarged, illustrating the actuating device in its lowermost position when severing a stamp;

Figure 6 is a longitudinal vertical sectional view on line 6—6 of Figure 2;

Figure 7 is an enlarged rear elevation of the stamp feeding means and its actuating device;

Figure 8 is a detail vertical sectional view illustrating the stamp severing means;

Figure 9 is a detail perspective view of the carrier for the stamp feeding fingers;

Figure 10 is an enlarged sectional view of the moistening device, and

Figure 11 is a similar view with the cover 60 for the moistening roller in operative position above the roller.

Referring more particularly to the drawings in which like reference numerals refer to corresponding parts in the several views, 1-65 designates each of three stamp containing units or housings which are similar in all respects to each other, and are adapted for containing and dispensing stamps of three different denominations, it being understood 70 that the invention is equally applicable to machines containing a larger number of stamp containing units. In most letter mailing, single stamp containiners are employed which operate to discharge, sever and affix 75 the stamp to an envelope. The present invention has to do with structures that do not affix the stamp, but permit it to be dispensed from a container, moistened and severed, ready for manual application to a package, 80 such machines being particularly intended for use where large volumes of parcel post mailing is required, or under other conditions where stamps of various denominations are frequently used. As the mechanism for 85 each stamp unit is the same, it will be necessary to describe the details of only one.

Referring to Figures 3 to 5, 2 designates the usual stamp roll or strip arranged on a suitable reel and adapted to be fed out through 90 an opening 3 in the housing. The strip is moved along by strip feeding instrumentalities comprising fingers 4 which are mounted on a vertically movable carrier 5 and held in normal or upper position by a spring 6. The 95 parts just referred to form no part of the present invention, except as they are combined with the structure now to be set forth in detail, and are generally similar to the mechanism disclosed in the previous patent 100 already referred to.

The actuating device for the feeding instrumentalities comprises a U-shaped plate 7 carrying a finger piece or key 8 and having its side walls slotted at 9. The slots 9 105 cooperate with pins 10 carried by lugs 11 on the carrier 5, while 12 is a spring connected at one end to one of said pins 10 and at the opposite end to the plate 7, and acting to hold said parts yieldably together so 110

that they normally move together, while the actuating device 7 is permitted an additional movement after the carrier 5 is stopped.

- 5 Downward movement of the carrier 5 is limited by its lower lugs 11 engaging the bottoms of the slots 13, see Figure 1, such downward movement of the carrier and fingers 4 being sufficient to eject a single stamp.
- 10 Upon releasing the key 8, the spring 6 returns the feeding instrumentalities upwardly to normal position, and this operation is repeated once for each stamp it is desired to eject. When the required number of 15 stamps have been dispensed, it is desirable to sever them from the roll or body of the stamp strip, and this is accomplished by severing means comprising a movable knife 15, see Figures 4 and 5, carrying a pin 16 that is guided in a slot 17 while 18 is a 20 spring which holds the movable knife in its normal or upper position.

The movable knife 15 cooperates with a stationary knife 19 to sever the stamp or 25 stamps, and 20 is a head or projection on the pin 16 lying in the path of a bottom wall 21 of the plate 7, or operating device. When it is desired to sever a stamp, instead of releasing the key 8 the moment the carrier 30 reaches the limit of its downward travel, as illustrated by the position of the parts in the center unit of Figure 1, the key 8 is depressed further until it occupies the position shown in the right hand unit of 35 Figure 1. This additional movement of the key 8 causes the bottom of plate 7 to engage the projection 20, moving the latter from the position shown in Figure 4 to that shown in Figure 5, and causing the movable knife to pass downwardly into cutting relation with the stationary knife 19 and sever the stamp, as shown in Figure 5.

The stamp is fed outwardly under a yoke-shaped guide or deflector 25, one of which 45 is provided for each stamp unit, and has lugs 26 pivoted at 27. The deflector 25 guides the ejected stamps into contact with a moistening roller 28 arranged in a water reservoir 29. Preferably there is a water 50 reservoir and moistening roll provided for each stamp containing unit, and the several reservoirs 29 are connected by passages 30, while 31 is a liquid supply tank common to the several reservoirs 29, and acting to 55 maintain the same level therein. 32 is a suitable container which may be placed in the neck 33 in inverted position and acts to supply the tank 31 with water.

At times, it may be desirable to dispense one or more stamps without moistening them, and to accomplish this, means are provided for selectively covering the moistening rollers to prevent their contacting with the gummed portion of the stamp. This may be effected by utilizing a cover such as 60 the plate 35 which is pivoted at 36 upon a support 37, the latter in turn being pivoted at 38 and held in position by a spring 39. When the cover 35 is not in use, it occupies the position shown in Figure 10, and if it is desired to cover its moistening roll, the plate 37 is swung outwardly against the action of spring 39, far enough to permit plate 35 to be swung upwardly and under the stamp deflector 25, whereupon if plate 37 is released, cover 35 will assume the position shown in Figure 11, and the stamp, while being ejected, will pass between the deflector 25 and cover 35.

While I have disclosed the invention with reference to a particular embodiment, it is not confined to the details set forth, and this application is intended to cover any changes or modifications coming within the intent of the improvements or scope of the following claims.

I claim:

1. A stamp dispensing machine comprising strip feeding instrumentalities, stamp severing means, and an actuating device for the feeding instrumentalities and stamp severing means, said actuating device being movable independently of the stamp severing means.
2. A stamp dispensing machine comprising strip feeding instrumentalities, stamp severing means, and an actuating device movable independently of the stamp severing means, said actuating device acting during the latter part of its stroke to engage and move the stamp severing means.
3. A stamp dispensing machine comprising strip feeding instrumentalities, a spring controlled stamp severing knife, a vertically movable actuating device operatively connected with the strip feeding instrumentalities and having a limited movement independently thereof, the stamp severing knife being supported independently of the actuating device and including an abutment in the path of the actuating device that is engaged thereby as the latter reaches the limit of its downward movement.

In witness whereof, I have hereunto signed my name.

WILLIAM F. SCHWEIGER.

5.

CERTIFICATE OF CORRECTION.

Patent No. 1,625,827.

Granted April 26, 1927, to

WILLIAM F. SCHWEIGER.

It is hereby certified that the assignee in the above numbered patent was erroneously described and specified as "Multiposter Company, Incorporated," whereas said assignee should have been described and specified as "Multipost Company, Incorporated," as shown by the records of assignments in this office; and that the said Letters Patent should be read with this correction therein that the same may conform to the record of the case in the Patent Office.

Signed and sealed this 31st day of May, A. D. 1927.

Seal.

M. J. Moore,
Acting Commissioner of Patents.
